UNITED STATES PATENT OFFICE.

WILLIAM B. FENN, OF PORT WASHINGTON, NEW YORK, ASSIGNOR TO MARGARET F. FENN, OF PORT WASHINGTON, LONG ISLAND, NEW YORK.

COVER FOR CONTAINERS.

Application filed March 13, 1920, Serial No. 365,460. Renewed July 23, 1924.

To all whom it may concern:

Be it known that I, WILLIAM B. FENN, a citizen of the United States, and a resident of Port Washington, in the county of 5 Nassau and State of New York, have made a certain new and useful Invention in Covers for Containers, of which the following is a specification.

This invention relates to covers for containers and is particularly directed to such containers as cans and the like which are employed for canning fruits, vegetables and other forms of foods.

The object of the invention is to provide 15 a cover which is simple in construction, economical to manufacture, and which is especially adapted for use in connection with sterilizing processes employed for sterilizing a can and its contents prior to the sealing 20 thereof, to thereby kill all bacteria and effect perfect preservation of the food in the finally sealed can.

Further objects of the invention will appear more fully hereinafter.

25 The invention consists substantially in the construction, combination, location and relative arrangement of parts, all as will be more fully hereinafter set forth, as shown by the accompanying drawing, and finally 30 pointed out in the appended claims.

Referring to the drawings:

Fig. 1 is a top plan view of a cover embodying my invention.

Figure 2 is a sectional view showing the 35 same in the position which will permit the entrance of fluid pressure into the can.

Figure 3 is a similar view showing the 40 position of the parts which will prevent the egress of the fluid from within the can.

The same part is designated by the same 45 reference character wherever it occurs throughout the several views.

It is among the special purposes of my present invention to provide a can which 50 will automatically permit steam or other fluid under pressure to enter the can as desired and which will prevent the steam or other fluid under pressure from escaping from the can.

I have found that the most efficient means 55 for effecting perfect sterilizing of fruits, vegetables, and other foods is to insert one or more cans in a closed receptacle and to thereafter supply a fluid pressure, for example, steam under pressure, to the closed

receptacle, whereby the steam enters a can, agitates the contents thereof, and effects the required sterilization. Thereafter the steam under pressure in the enclosed receptacle is exhausted and it is desired to retain the steam 60 under pressure which has entered the can within the can. Various means have heretofore been employed for accomplishing this purpose and it is among the special purposes of my present invention to provide a can 65 which automatically effects this result where such a process is employed. I wish it to be understood, however, that the construction of a container embodying my invention is to be by no means limited in its use to 70 the foregoing process employed in effecting sterilization of canned products as its adaptability for other uses will be apparent and it is the structure of the can and, more particularly, the cover thereof, which constitutes the present invention. 75

In accordance with my invention I provide a cover 1 which is adapted to be crimped in any desired manner, for example, the usual overlapping arrangement illustrated at 2 to the wall 3 of the can. In one form of my invention the cover is provided with an annular depression 4 stamped therein with a plurality of circular depressions 5 annularly disposed in the annular depression 4, provided with a perforation 6 through the same. To reinforce the annular depression 4 and to afford a tight seal I provide an annular reinforcing plate 7 of any suitable material interposed between the cover and the cup-shaped member 8. The cup-shaped member 8 surrounds the annular depression 4 on the bottom surface of the cover and is suitably secured to the bottom surface of the cover in any 80 suitable manner, for example, welded or soldered thereto. The cup-shaped member 8 is provided with an upward central depression 9 which is adapted to fit into the central upwardly extending depression 100 formed in the cover 1 by means of the interior wall of the annular depression 4 and the reinforcing plate 7. The cup member 8 is of such depth as to normally seat thereon the second depression 5 of the cover 1. 105 Normally the can in its assembled position is shown in Figure 3 with its cover applied. Now it will be readily apparent that when the fluid pressure is applied, for example, in the manner above indicated, where the 110

can or container is enclosed in an enclosed receptacle, and fluid pressure is supplied thereto, the pressure passes through the orifices 6, bending downwardly the cup-shaped member 8 in the manner illustrated in Figure 2, whereby a path for the fluid pressure is established, through the orifice 6 in the annular depression 5 between the cover 1 and the cup-shaped member 8, 10 through the orifice 10 of the member 8 into the can. When the pressure is exhausted from the closed receptacle it will be apparent that the pressure within the can will cause the cup-shaped member 8 to contact 15 tightly with the cover 1 and its reinforcing member 7 to thereby prevent leakage of the fluid pressure from out of the can. To afford a permanent seal, the depressions 5, 6, etc., if desired, may be soldered, or otherwise 20 permanently sealed.

Many other ways may readily be devised for accomplishing the purposes of my present invention and I therefore wish it to be understood that I do not desire to be limited 25 to the shape, size or material, as I consider it to be my broad invention to provide a container of any shape, size or material which will automatically permit entrance 30 of fluid pressure and will automatically prevent the exit thereof.

Having now described my invention and shown one structure embodying the principles thereof, what I claim as new and of my own invention and desire to secure by Letters Patent is:—

1. In a container for sterilizing food products, the combination of means for permitting steam pressure to enter said container, and means actuated by the steam pressure admitted into the container for preventing said steam pressure within the container from escaping therefrom.

2. In a container for sterilizing food products, the combination of means actuated by steam pressure for permitting said steam pressure to enter said container, and means actuated by said steam pressure within the container for preventing said steam pressure within the container from escaping therefrom.

3. In a container for sterilizing food products, the combination with a container of means for permitting steam pressure to enter said container, and means actuated by the steam pressure within the container for sealing the container when the supply of steam pressure to said container is shut off.

4. In a container for sterilizing food products, the combination of means actuated

by steam pressure for permitting said steam pressure to enter said container, and means actuated by the steam pressure within the container for sealing the said container when the steam supply to said container is shut off.

5. In a container, a cover provided with a perforation therethrough, a normally closed tortuous passage for establishing communication between said perforation and the interior of said container, and means actuated by fluid pressure in the exterior of said container for opening said passage.

6. In a container, a cover provided with a perforation therethrough, a normally closed tortuous passage for establishing communication between said perforation and the interior of said container, means actuated by fluid pressure in the exterior of said container for opening said passage, and means actuated by the fluid pressure within the container for closing said passage.

7. A cover for containers including an annular depression with a perforation therethrough, a circular flexible member secured to the outer periphery of said annular depression within the container and formed with its center upwardly displaced to form a snug fit with the center of said cover, and provided with a central opening.

8. A cover for containers including an annular depression with a perforation therethrough, a circular flexible member secured to the outer periphery of said annular depression within the container and formed with its center upwardly displaced to form a snug fit with the center of said cover, and provided with a central opening, and a reinforcing plate of annular form interposed between the center of said cover and the center of said member.

9. In a container, in combination a body and a cover, one of said members having an inlet opening associated therewith and a flexible diaphragm having an opening offset from the first mentioned opening movable to close said openings upon internal pressure and to open the same upon external pressure.

10. In a container, a body and a cover therefor having an inlet port therein, and a flexible diaphragm mounted to be movable into and out of sealing contact with the cover, said diaphragm having an aperture located therein offset relative to said port.

In testimony whereof I have hereunto set my hand on this 8th day of March, A. D. 1920.

WILLIAM B. FENN.
